INVENTOR

George J. Becker.

BY
J. B. M. Givens.
ATTORNEY.

UNITED STATES PATENT OFFICE.

GEORGE J. BECKER, OF ANNADALE, NEW YORK.

PIANO KEY.

Application filed August 25, 1923. Serial No. 659,296.

My invention relates to an improvement to the key of a piano action whereby it is not necessary to remove the key for padding it up to get the same in proper position.

5 My invention consists of means whereby it is possible to assemble in their respective positions each and every key belonging to the action, then to adjust each separate key up or down as the case may require so as to attain its proper position.

10 My invention is simple, durable and expeditiously manipulated, as well as being cheap and very easily applied to any make of piano.

15 With the foregoing and other objects in view, further objects and advantages will appear as the description of the invention is hereinafter developed.

20 Referring to the drawings wherein is shown what is now considered to be the preferred form of my invention:

Figure 1 is a partial view of a piano action, showing my invention in operative position thereon;

25 Figure 2 is an enlarged side elevation of a portion of the key showing the position of the elevating and lowering means;

Figure 3 is a longitudinal sectional view of the same showing the finger depressed 30 to raise the key;

Figure 4 is a side view of the same part of the key showing the side guides applied, and

35 Figure 5 is a modified form of guide.

The assembling of the many keys on the key board of a piano is quite long and tedious, each and every key has to be raised or lowered to the proper height and at the same time to the proper touch. The operation

40 requiring the placing and removal of each key many times from the pin on the rocker block so as to place on the pin or remove therefrom as the case may require paper washers or punchings that are used for the purpose.

45 With the herein improvement about one tenth of the time is required for the proper positioning of a key board of 88 notes.

Referring to the drawings in which like 50 parts designates the same reference numerals. Referring particularly to Figure 1, the ordinary base or bed of the piano is designated by the numeral 6, upon which the various keys are assembled. The bed is provided at its front end with a rail pin 7 which is usually provided with a felt punching or

washer 8, while 9 is the balancing rail block, from the center of which extends upwardly a pin 10 which holds a felt punching 11. A suitable distance in the rear is placed a rear 60 cloth or felt 12 which cushions the key on its return.

The key 13 is of the ordinary design and material and having therein an opening 14 to receive the pin 7, and an opening 15 of 65 an angular variety for allowing the key to rock on the pin 10, at the same time having such proportions as to hold therein a felt lining 16 that prevents the pin from coming in contact with the wood, said key having 70 the usual button 17 thereon, as well as the rear button 18, which lies immediately under the capstan screw 19, while immediately above the latter is located the abstract 20, which in turn operates the mechanism for 75 the particular note. The mechanism as shown in the illustration is about the usual arrangement in upright pianos, yet the key mechanism shown herein is, as has been noted, not limited to such pianos. That part 80

of the key 13, that lies immediately above the balance rail block 9, is preferably cut as shown at 21, forming thereby a finger 22, said finger being reinforced at its rear end by a spring 23, that is countersunk and held in position by suitable screws 24, thus having no projecting parts on said key. While the upper forward end of said finger is cupped as at 25, which cup receives and holds the inner free end of a screw 26, the 90 head 27 of which lies to the forward end of the key button 17 and thereby affords easy access to the same for the proper adjusting of such key to the desired height.

With my improved key it will no longer 95 be necessary to lift each key from its pin 10 to build it up, to the desired height, which in the parlance of the trade is known as key leveling. In effecting this leveling operation, the key is set to the touch and, as has 100 been before noted, very often is required to be removed many times before the correct leveling is accomplished.

With my improvement the raising and lowering of any key on any piano is effected 105 by inserting a screw-driver in the slot of the screw 26 and turning the same it will cause the finger 22 to be pushed downwardly against the action of the spring 23, and thereby lift the key to the desired height. The 110 end of the screw being reduced, and the head of the finger 22, being cupped forms a

housing for the end of the screw, and thereby forms one means whereby the finger is at all times kept in vertical alignment with the key. Again by withdrawing the screw 26, the finger will permit the key to be lowered the desired distance.

While the finger 22 is shown integral with key 13, with the narrow part, forming in conjunction with the spring 23, a hinge 10 about which the finger bends, it will be understood that the said finger could be of a separate piece or part adapted to be set into the opening in the key, with the spring 23 acting in the same capacity.

Again to insure the finger at all times being held secure in place, there may be secured to the side of the finger aperture, a part 28, (see Figure 4) located in a recess on each side of the key, of course when such guards are used corresponding recesses must be provided in the finger, so that there will be no projecting parts from the key to interfere with the proper working and assembling of the keys. Of course the same may be accomplished by having an extension 29, secured to the finger, and its free end housed in a slot 30, it being very important that such finger being at all times in strict alignment with the key.

In accordance with the provision of the patent statutes I have herein described the principal forms of my invention which I now consider to represent the best embodiment thereof, but I desire to have it understood that the various forms are only illustrative and that the invention can be carried out in other ways other than those shown and described, but all are intended to come within the scope of the claims.

Having described my invention, what I claim and desire to secure by Letters Patent is:

1. A device for leveling piano keys comprising a finger formed by cutting into the material of the key, and said finger being normally seated in the cutaway portion of the key, a spring device attached to the key and extending across the point of connection between the key and the finger to resist displacement of the finger from the cutaway portion of the key, said finger being provided with a recess at its free end, and an adjusting element extending through the key in an angular direction and having its end received in the recess to hold the finger in alignment with the body of the key, and to positively move the finger out of the cutaway portion of the key.

2. A device for leveling piano keys comprising a finger formed by partially severing a section of the material of the key, and said finger being normally seated in the cutaway portion so formed in the key, an elongated spring attached at one of its ends to the body of the key and extending across the point of connection between the key and the finger to resist displacement of the finger from the cutaway portion of the key, said finger being provided with a cupped shaped recess at its free end, and an adjusting screw extending angularly through the key and having its end received in the recess in the finger to hold the finger in alignment with the body of the key, and to positively move the finger out of the cutaway portion of the key.

In testimony whereof I affix my signature.
GEORGE J. BECKER.
